JOHN W. KISSAM, OF NEW YORK, N. Y.

Design No. 3,246, dated November 17, 1868.

DESIGN FOR A SCALE-DISH.

The Schedule referred to in these Letters Patent and making part of the same.

To all whom it may concern:

Be it known that I, JOHN W. KISSAM, of the city, county, and State of New York, have invented a new and original Design for a Scale-Bottom; and I do hereby declare the following to be a full, clear, and exact description thereof, which will enable those skilled in the art to make and use the same, reference being had to the accompanying drawing, forming part of this specification, in which drawing—

Figure 1 represents a transverse section of this invention.

Figure 2 is a perspective view thereof.

Similar letters indicate corresponding parts.

This invention relates to a design for a scale-bottom, whereby such bottom receives a distinguishing appearance of strength and solidity.

A represents one of my scale-bottoms, which is made

concave, as usual. The edge of this bottom is turned down so as to form a broad rim *a*, the edge of which is filled up by a stout wire, *b*.

By this rim a new and particular appearance of strength and solidity is given to my scale-bottoms, whereby I am enabled to distinguish the same from scale-bottoms made in the usual form or shape.

Having thus described my invention,

What I claim as new, and desire to secure by Letters Patent, is—

The design for a scale-bottom, as herein shown and described.

JOHN W. KISSAM.
